CAR COUPLER

William J. Metzger, Cleveland, Ohio, assignor to
National Malleable and Steel Castings Company, Cleveland, Ohio, a corporation of Ohio

Application April 1, 1939, Serial No. 265,499

10 Claims. (Cl. 213—166)

This invention relates to car couplers and more particularly to the coupler lock operating mechanism.

A feature of the invention is in the mounting of the rotor lever for actuating the lock, wherein the rotor lever is pivotally mounted on the outside of a pair of spaced lugs depending from the bottom of the coupler and the lever is joined with the lock by members positioned in the space between the lugs. A further feature resides in the connections between the rotor lever and the members joining the lever and lock whereby rotary movement of the lever is translated into vertical movement for raising the lock. Other objects and advantages of my invention will become apparent from the following description taken in connection with the following drawings, in which:

Figure 1 is a partial vertical sectional view of a coupler embodying my invention in locked position, the lock and lock operating mechanism being shown in full.

Figure 2 is a side elevational view partly in section of the coupler showing the mechanism in knuckle thrown position, with the rotor lever shown in full.

Figure 3 is a fragmentary view of the coupler showing the front of the lock operating mechanism, taken generally along line 3—3 of Fig. 1.

Figure 4 is an elevational view of the lock operating mechanism, showing the uncoupling rod side; and

Figure 5 is a sectional plan view taken along line 5—5 of Fig. 3.

Referring to the drawings, there is shown a coupler head 10 having a knuckle 11 pivotally attached thereto and a shank 13. Depending from the bottom of the coupler are transversely spaced elements 14 each having a downwardly extending lug 15. Projecting outwardly from each lug 15 is a horizontal trunnion 16. Pivotally mounted on trunnions 16 is a rotor lever member designated generally by numeral 17. The rotor lever is provided with hook portions 18 which engage the trunnions 16 and are precluded from disengagement therefrom in all operative positions of said member by overlapping curved portions 19 of side walls 20 of elements 14. Positioned between elements 14 and extending vertically upward through an opening 21 in the floor of the coupler is the lock lift member 22 which has an arm 23 at its upper end adapted to be received by the eye 24 of lock 25. Member 22 is formed with a vertical slot 26 and pivotally mounted therein by means of

pin 30 is the L-shaped link 31 which is adapted to cooperate with the rotor lever to transmit lifting movement therefrom to member 22. The central portion of rotor lever 17 is bifurcated, 5 as at 32, forming ears 33. Arm 34 of link 31 extends into bifurcation 32 and by means of a pin 36 passing through slot 35 of arm 34 and ears 33, the link is both pivotally and slidably connected to the rotor lever. Pin 36 may be held in place by a cotter 37.

In locked position of the coupler, as shown in Figs. 1 and 4, link 31, due to the weight of arm 34 and to the rotor lever acting thereon, assumes a position in which the upper end of vertical portion 38 underlies bottom wall 39 of the coupler to effectively preclude accidental upward creeping or jumping of the lock. The forward movement of portion 38 is limited by the engagement of the underside of arm 34 with the stop or end piece 40 of member 22. At one end of the rotor lever there is provided an eye 41, integral with one of hook portions 18 and extending laterally therefrom, adapted to receive the hook portion 42 of uncoupling rod 43. Depending from eye 41 is lug 44 which cooperates with portion 45 of hook 42 to impart rotational movement from the uncoupling rod to the rotor lever. The other end of the rod is pivotally connected to the car by a suitable bracket 46 and terminates in a handle 47. Although the rotor lever is shown with only one eye 41 it is to be understood that a similar eye may be provided at the other end so as to permit operation of the mechanism from either side of the car.

In the uncoupling operation, upon the actuation of the rotor lever by the uncoupling rod the first action is to tilt link 31 rearwardly to a position in which the upper end of vertical portion 38 clears wall 39 and is in engagement with a stop 48 in member 22. This movement is effected by the cooperation of pin 36 with the upper surface 49 of slot 35. Link 31 and member 22 may now be raised as a unit into either lockset position or knuckle thrown position, as may be desired. As the members and the lock are raised, pin 36 travels along its path of revolution and moves forwardly in slot 35 until it has reached the outermost point along its arc of travel, whence it moves in the opposite direction toward the other end of the slot until it has reached the position shown in Fig. 2 with the knuckle thrown. It will be observed that slot 35 is so positioned in link 31 that during the entire locking operation the upper surface 49 thereof slopes downwardly so that when pin 36

is moving forwardly in the slot, it is moving uphill with respect to said surface, while when it is moving rearwardly in the slot, it moves downhill with respect to said surface. As greater effort is required to operate the mechanism when the knuckle is being thrown than at the start of unlocking, this downhill action occurring during the latter period of the operation increases the mechanical advantage of the mechanism so that easier and smoother operation is obtained during opening of the knuckle. Member 22 is prevented from moving rearwardly during operation of the mechanism by the stops 59 which join elements 14 at the lower ends thereof.

To disassemble the mechanism the uncoupling rod is first disengaged from the eye 41. Pin 36 is next removed after which the rotor lever is free to be swung in a counterclockwise direction, as viewed in Fig. 1 until the hook portions 43 have been released from the trunnions.

The terms and expressions which I have employed are used as terms of description and not of limitation, and I have no intention, in the use of such terms and expressions, of excluding any equivalents of the features shown and described or portions thereof, but recognize that various modifications are possible within the scope of the invention claimed.

What I claim is:

1. In a car coupler comprising a head and a pivotally mounted knuckle, a lock for said knuckle, support means comprising a pair of elements depending from said coupler, each of said elements having a laterally outwardly extending bearing portion, a lift lever for operating said lock positioned between said elements and extending through an opening in the bottom of said coupler, said lever being formed with a vertical slot, a link pivotally connected to said lever within said slot and a rotor lever pivotally mounted on said bearing portions and connected to said link, said link being adapted to cooperate with said rotor lever and lift lever to transmit lifting movement from said rotor lever to said lift lever upon actuation of said rotor lever.

2. In a car coupler comprising a head and a pivotally mounted knuckle, a lock for said knuckle, support means comprising a pair of elements depending from said coupler, each of said elements having a laterally outwardly extending bearing portion, a lift lever for operating said lock positioned between said elements and extending through an opening in the bottom of said coupler, said lever being formed with a vertical slot, a link pivotally connected to said lever within said slot, said link comprising an arm having a slot therein, a rotor lever pivotally mounted on said bearing portions, and means extending through said last named slot for pivotally and slidably connecting said link to said rotor lever, said link being adapted to cooperate with said rotor lever and lift lever to transmit lifting movement from said rotor lever to said lift lever upon actuation of said rotor lever.

3. In a car coupler comprising a head and a pivotally mounted knuckle, a lock for said knuckle, support means comprising a pair of elements depending from said coupler, each of said elements having a laterally outwardly extending bearing portion, a lift lever for operating said lock positioned between said elements and extending through an opening in the bottom of said coupler, said lever being formed with a vertical slot, a link pivotally connected to said lever with-

in said slot, said link comprising an arm having a slot therein, a rotor lever pivotally mounted on said bearing portions, said rotor lever having a pair of spaced ears, said arm extending between said ears, and means extending through said last named slot and ears pivotally and slidably connecting said link to said rotor lever, said link upon actuation of said rotor lever being adapted to transmit lifting movement therefrom to said lift lever.

4. In a car coupler comprising a head and a pivotally mounted knuckle, a lock for said knuckle, support means comprising a pair of elements depending from said coupler, each of said elements having a laterally outwardly extending bearing portion, a lift lever for operating said lock positioned between said elements and extending through an opening in the bottom of said coupler, said lever being formed with a vertical slot, a link pivotally connected to said lever within said slot, said link comprising an arm having a slot therein, a rotor lever pivotally mounted on said bearing portions, and pivot means extending through said link slot and rotor lever, said last named means upon actuation of said rotor lever being adapted to cooperate with the top wall of said slot to transmit lifting movement from said rotor lever to said link and lift lever.

5. In a car coupler comprising a head and a pivotally mounted knuckle, a lock for said knuckle, support means comprising a pair of elements depending from said coupler, each of said elements having a laterally outwardly extending bearing portion, a lift lever for operating said lock positioned between said elements and extending through an opening in the bottom of said coupler, said lever being formed with a vertical slot, a link pivotally connected to said lever within said slot, said link comprising an upwardly extending portion adapted to underlie a portion of said coupler when said coupler is in locked position to limit creeping of said lock, and a rotor lever pivotally mounted on said bearing portions and being pivotally connected to said link, said rotor lever being adapted to rotate said link to withdraw said upwardly extending portion from beneath said portion of the coupler and thereafter to impart a lifting movement to said link to raise said lock to unlocked position.

6. In a car coupler comprising a head, a knuckle pivotally attached thereto, a lock for said knuckle, support means comprising a pair of elements depending from said coupler, each of said elements having a laterally outwardly extending bearing portion, a rotor lever pivotally mounted on said portions, a lift lever for operating said lock positioned between said elements and extending through an opening in the bottom of said coupler, said lever being formed with a vertical slot, link means pivotally connected to said lever within said slot adapted to transmit lifting movement from said rotor lever to said lift lever, said link comprising an arm having a downwardly extending slot therein, and pivot means extending through said link slot and rotor lever connecting said link thereto, said last named means upon actuation of said rotor lever being constructed and arranged to slidably engage the top wall of said link slot so as to move uphill with respect thereto during the beginning of the unlocking operation and downhill with respect thereto during the completion of the operation.

7. In a car coupler comprising a head and a pivotally mounted knuckle, a lock for said

knuckle, support means comprising a pair of elements depending from said coupler, each of said elements having a laterally outwardly extending bearing portion, a lift lever for operating said lock positioned between said elements and extending through an opening in the bottom of said coupler, said lever being formed with a vertical slot, a link pivotally connected to said lever within said slot, said link comprising an upwardly extending portion adapted to underlie a ledge on said coupler when said coupler is in locked position to limit creeping of said lock, and a rotor lever pivotally mounted on said bearing portions and being connected to said link, said link and rotor lever being constructed and arranged so that upon initial actuation of said rotor lever said link is withdrawn from underneath said ledge and upon further actuation said link is adapted to transmit lifting movement from said rotor lever to said lift lever.

8. A car coupler having an opening in the bottom thereof, a pivotally mounted knuckle, a vertically movable lock for said knuckle having a leg extending downwardly through said opening, means comprising a bell crank lever pivotally joined to said leg having an upwardly extending portion normally underlying a portion of said coupler for limiting upward movement of said lock, support means comprising two elements depending from said coupler directly opposite each side of said leg, a lug extending laterally outwardly from each of said elements, and means pivotally mounted on said lugs adjacent the leg of said lock having a projection extending forwardly from the pivotal mounting thereof, said first named means having a forwardly extending slotted arm adjacent said projection, and means passing through said projection and slot for pivotally joining said projection and arm.

9. A car coupler having an opening in the bottom thereof, a pivotally mounted knuckle, a vertically movable lock for said knuckle having 40

a leg extending downwardly through said opening, means pivotally joined to said leg having an upwardly extending portion normally underlying a portion of said coupler for limiting upward movement of said lock, support means comprising two elements depending from said coupler directly opposite each side of said leg, a lug extending laterally outwardly from each of said elements, means pivotally mounted on said lugs adjacent the leg of said lock having a projection extending forwardly from the pivotal mounting thereof, said first named means having a forwardly extending slotted arm adjacent said projection, and means passing through said projection and slot for pivotally joining said projection and arm.

10. A car coupler having an opening in the bottom thereof, a pivotally mounted knuckle, a vertically movable lock for said knuckle having a leg extending downwardly into said opening, means pivotally joined to said leg having an upwardly extending portion normally underlying a portion of said coupler for limiting upward movement of said lock, support means comprising two elements depending from said coupler directly opposite each side of said leg, a lug extending laterally outwardly from each of said elements, means pivotally mounted on said lugs adjacent the leg of said lock having a projection extending forwardly from the pivotal mounting thereof, said first named means having a slotted arm adjacent said projection, and means passing through said projection and slot for pivotally joining said projection and arm, said slot being so positioned in said arm that the upper wall thereof slopes downwardly and forwardly during movement of said lock from locked to unlocked position.

WILLIAM J. METZGER.
